(57) **CLAIM**

The ornamental design for a hooded blanket coat, as shown and described.

DESCRIPTION

FIG. 1 is a front, right and top perspective view of a hooded blanket coat, showing my new design;

FIG. 2 is a rear, left and bottom perspective view thereof; FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged detail view taken from line 9 in FIG. 1;

FIG. 10 is an enlarged detail view taken from line 10 in FIG. 1; and,

FIG. 11 is an enlarged detail view taken from line 11 in FIG. 7.

The dash-dash broken lines of the hooded blanket coat depict portions of the article that form no part of the claimed design. The dash-dash broken lines at the openings of the hooded blanket coat define a boundary line to the claimed design that form no part of the claimed design. The dash-dot-dash broken lines define the regions of the enlarged detail views and form no part of the claimed design.
